FASTENER

Marshall W. Broyles, 217 N. Harrison St.,
Alexandria, Ind.
Filed Sept. 19, 1961, Ser. No. 139,307
5 Claims. (Cl. 24—205.11)

The present invention generally relates to a fastener assembly and more particularly to such a fastener adapted for use in combination with garments and the like.

The use of slide fastener assemblies generally referred to as "zippers" has become quite prevalent in the garment industry and in many other orientations where flexible components are to be connected together. Inasmuch as the interlocking hooks and the slide of a slide fastener cannot extend completely to the edge of a garment or the like, it is usual to provide some type of detachable fastener at the edge of the garment for retaining the end edges of the opening in the garment in closed relation. In ladies' dresses, there is usually provided a small loop and hook assembly at the top edge of the vertical opening in the back of a dress. This hook and loop assembly is usually quite difficult to interengage and leaves considerable to be desired as far as neatness is concerned. Further, the loops are quite often formed of threads, cord or the like which have a relatively short life. Accordingly, it is the primary object of the present invention to provide a fastener assembly for use at the upper edge of an opening in the rear of a dress or similar garment which is easily manipulated and which retains the connected edges of the garment in direct alinement and in a neat, flat and unwrinkled condition.

Still another object of the present invention is to provide a fastener assembly for a garment or the like including a longitudinally elongated male and female resilient element which are interlocked and disengaged by exerting lateral force on the male and female elements.

Still another object of the present invention is to provide a fastener assembly in accordance with the preceding objects having a mounting plate for each of the male and female elements engaged with the slide fastener tape and stitched to the tape or garment by virtue of a plurality of apertures provided therein for receiving a sewing machine needle so that the fastener assembly may be attached directly to the tape or garment by virtue of ordinary tailoring techniques.

Yet another important object of the present invention is to provide a fastener assembly for the top edge of a vertical opening in the back of a dress having forms attached thereto for shaping and retaining the shape of the top edge portion of the dress adjacent the fastener assembly.

Another important feature of this invention is the provision of a fastener assembly which can be attached to any material in combination or without the slide fastener assembly and which may be employed for various uses such as in combination with tent flaps, canvas bags, various garments and the like.

Yet another very important feature of this invention is to provide a fastener assembly which is quite simple in construction, easy to operate, secure in its fastening operation, dependable and long lasting and generally inexpensive to manufacture while yet being easily assembled with a garment or the like.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a fragmental elevational view with portions shown in section illustrating the fastener assembly

2

of the present invention assembled with an edge of a garment or the like;

FIGURE 2 is a vertical sectional view, on an enlarged scale, taken substantially upon a plane passing along section line 2—2 of FIGURE 1 illustrating the relationship of the fastener assembly with the garment;

FIGURE 3 is a transverse, plan sectional view, on an enlarged scale, taken substantially upon a plane passing along section line 3—3 of FIGURE 1;

10 FIGURE 4 is a perspective view of the fastener assembly of the present invention;

FIGURE 4A is an elevational view of the fastener assembly;

FIGURE 5 is a view similar to FIGURE 1 but with 15 the forming or shaping attachments mounted thereon;

FIGURE 6 is a detailed sectional view, on an enlarged scale, taken substantially upon a plane passing along section line 6—6 of FIGURE 5 illustrating the manner of attachment of the shapers to the fastener assembly;

20 FIGURE 7 is a perspective view of one of the shaping or forming devices;

FIGURE 8 is an elevational view illustrating a decorative ornament attached to the fastener assembly of the present invention;

25 FIGURE 9 is a detailed sectional view taken substantially upon a plane passing along section line 9—9, on an enlarged scale, illustrating the assembly when the decorative ornament is attached thereto;

FIGURE 10 is a perspective view of the ornament clip 30 illustrated in FIGURES 8 and 9;

FIGURE 11 is a view similar to FIGURE 1 but illustrating a form of the invention in which the edges of the opening are overlapped; and

FIGURE 12 is a transverse, plan sectional view, on an 35 enlarged scale, taken substantially upon a plane passing along section line 12—12 of FIGURE 11.

Referring now specifically to the drawings, the numeral 10 generally designates the fastener assembly of the present invention which includes a male fastener element 12 and a female fastener element 14 both of which are adapted to be disposed in a garment 16 or the like at the upper end of a slide fastener assembly 18 having the usual slider 20 associated therewith and the usual mounting tape 22 for the interlocking elements of the slide fastener.

45 The male element includes a mounting plate 24 having a reverse bend 26 at the upper edge and a reverse bend 28 at the lower edge with the reverse bend 26 continuing downwardly in the form of a second plate 30 lying alongside of and against the plate 24 thus forming a generally rectangular mounting plate of rectangular construction and the reverse bend 28 clamps over the lower edge of the plate 30.

50 The female member 14 also includes similar mounting plates 30 and 32 having a reverse bend 34 at the upper edge and a reverse bend 36 at the lower end. As illustrated in FIGURES 2 and 4, the reverse bend 36 extends upwardly into overlying relation to the bottom end of the plate 32 as designated by reference numeral 38 thus forming a rigid plate having a loop 40 at the upper end thereof which is defined by the reverse bend.

55 Each of the fastener elements 12 and 14 includes a plurality of laterally elongated slot-like openings 42 therein which receive a sewing machine needle so that the tape 22 may be readily secured to and attached to the 60 fastener elements 12 and 14.

The male fastener element 12 includes a pair of inwardly 65 extending notches 44 in the edge thereof facing the female fastener element and the plate 30 has a projecting tongue 46 centrally thereof whereby the upper and lower edges 70 are generally parallel to the notches 44. The outer end of the tongue 46 is formed into a generally cylindrical member 48 forming a male snap fastener element. The

plate 24 has a similarly projecting tongue 50 shorter than the tongue 46 which terminates in a reverse bent portion 52 as illustrated in FIGURE 4.

The reverse bends 26 and 28 have notches 54 formed therein and the tongue 46 and the reverse bent portion 52 of the tongue 50 is provided with an opening 56 all facilitating the attachment of the device to the tape. The tongue 52 will normally clamp the edge of the tape 22 as illustrated in FIGURE 3 thus securely attaching the edge of the tape to the fastener assembly. Also, the lower inner edge of the plate 24 formed by the notch 44 is provided with a return bent portion 58 also for clamping engagement with the tape thus securing the male fastener assembly to the tape by virtue of the tape 22 proceeding along one surface of the male fastener element and being received and clamped by the reverse bent portions 52 and 58 and then being folded downwardly over the reversely curved top edge 26 and extending along the other surface thereof with stitching extending through the tape and the various apertures for receiving and retaining the fastener elements securely in place.

The female fastener element 14 includes a tongue 60 on the plate 32 and a tongue 64 on the plate 31 which are defined by notches 66. The tongues 60 and 64 are formed into partial cylindrical socket-forming members 68 and the outer edge of each tongue is provided with a reverse bent portion 70 which clampingly engages the tape members 22 against the outer surface of the socket-forming members 68 as illustrated in FIGURE 3. The lower end of the plate 31 is also provided with a reverse bent portion 72 for engaging the tape 22 and a pair of projecting dimples 74 are provided on the plate 32 for leveling the female fastener element 14 when assembling it with a garment inasmuch as the reverse bent portion 70 would normally orientate the female fastener element in inclined relation when inserting it under a sewing machine head. Thus, with this assembly, the fastener elements are assembled with the top edge of the slider assembly tape and the garment elements 76 and 78 which are interconnected by the fastener elements may be secured thereto in any suitable conventional manner by the use of the stitching or the like.

In FIGURES 5-7, the same type of construction as far as the fastener assembly is illustrated except that the top edges of the garment portions 76 and 78 are inclined as indicated by numeral 80. This is in conjunction with a usual V-shaped collar or upper edge. To form and shape this collar, there is provided a pair of forms of generally triangular shape and generally in the form of a triangular plate 82. The triangular plate 82 has a tab 84 at the lower edge thereof separated by a slot 86 whereby the tab 84 may slide into the loop 40 formed at the upper edge of the fastener elements thus securing the forms 82 in place with the inclined edge thereof conforming with and engaging the inclined edge of the garment thus shaping and retaining the shape of the edge of the garment for retaining it in neat, unwrinkled and straight condition.

In FIGURES 8-10, there is disclosed an arrangement in which a tab 88 is disposed exteriorly of the garment sections 76 and 78 and a tab is disposed on each of the fastener elements and each tab 88 includes a decorative ornament 90 which may conveniently be in the form of an alphabetical letter designating the initials of the person wearing the device. The tab 88 is attached to one edge of an inverted U-shaped clip 92 that extends over the top edge of the fastener elements 12 and 14 as illustrated in FIGURE 9. The resiliency of the material from which the clips 92 are constructed will retain the clips in position and the tabs 88 will extend out through the edge of the garment in any suitable manner so that they will be observable from the rear surface thereof.

FIGURES 11 and 12 illustrate a form of the invention in which one of the tongues 64' is extended into an elongated leg 94 overlapping the male fastener element where-

by the garment section 76 will have a portion 96 overlapping the adjacent edge of the garment portion 78 thus concealing the fastener assembly. The juncture between the tongue 64' and the extension 94 still forms a socket for receiving the male cylindrical member 48.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A fastener assembly comprising a male fastener element and a female fastener element, said male element including a plate having a lateral tongue on one edge thereof, said tongue terminating in a substantially cylindrical end edge, said female element including a plate having a pair of projecting tongues terminating in inwardly facing semicylindrical sockets at the end edges thereby defining a socket for receiving the end edge of the tongue on the male member, said tongues being of less width than the plates and constructed of resilient material for frictional locking engagement, each of said plates including a plurality of aligned openings whereby a sewing machine needle may project therethrough for stitching the elements of fabric members adapted to be connected thereby, each of said plates being constructed from a reversely folded member adapted to be positioned within the reversely folded end portion of a slide fastener mounting tape thus mounting the assembly at the end of a slide fastener, each of said tongues on the female element being reversely folded to clampingly engaging the edge of the slide fastener tape.

2. The combination of claim 1 wherein one edge of each plate includes a reversely folded hook on the edge thereof from which the tongues project thereby clampingly engaging the slide fastener tape.

3. The combination of claim 2 wherein said plate on the female element is provided with a pair of dimple-like projecting members for leveling the female element when moving under a sewing machine head.

4. In combination with a garment having an opening therein closed by a slide-type fastener assembly including longitudinal mounting tapes for the interlocking elements of the assembly, a friction grip-type of fastener assembly located at the end of the opening in alignment with the slide fastener assembly and including a male fastener element and a female fastener element, said male fastener element including a plate having a substantially cylindrical tongue on one edge thereof with the tongue being generally in alignment with the interlocking elements of the slide fastener assembly, said female element including a plate having a pair of projecting tongues defining inwardly facing semi-cylindrical sockets at the edge thereof generally in alignment with the interlocking fasteners of the slide fastener assembly for frictionally receiving the cylindrical tongue on the male fastener element, said plates being disposed in overlying relation to the mounting tapes of the slide fastener assembly and including a plurality of longitudinally spaced openings for receiving a sewing machine needle therethrough whereby the plates may be stitched to the mounting tapes of the slide fastener assembly, each of said plates being reversely folded at the top end edge thereby defining a loop, and a triangular extension for each plate, said extension including a tab parallel to the bottom edge but spaced therefrom for sliding interlocking engagement with the loop at the top edge of each of the plates thereby forming a triangular upper end for the plate for engagement with the fabric of the garment for forming the fabric into substantially a V-shaped junction at the edge of the opening.

5. A fastener assembly for garments and the like comprising a male fastener element and a female fastener element, said male fastener element including a plate having

a plurality of longitudinally aligned and mutually spaced aperture means formed therein for receiving a sewing needle to enable the plate to be attached to the garments, certain of said aperture means being defined by inwardly extending notches communicating with one side edge of the plate, said one side edge of the plate having a centrally disposed projecting tongue forming the inner edges of the notches and projecting beyond said one edge of the plate, said tongue terminating in a substantially cylindrical end portion disposed beyond the lateral confines of the plate, said female fastener element including a plate having a plurality of longitudinally aligned and spaced aperture means therein for receiving a sewing needle for enabling the plate to be attached to a garment, certain of said aperture means being formed by inwardly extending notches communicating with one side edge of the plate, the central portion of the plate having a pair of projecting tongues defining side edges of the notches and projecting beyond the corresponding edge of the plate, said tongues terminating in a pair of generally arcuate members having concave surfaces facing each other to form a generally split cylindrical socket disposed beyond the lateral confines of the plate for frictional engagement

with the tongue on the male fastener element, each of said plates being of laminated one-piece construction with the layers of each plate being reversely folded at one end thereof thereby rigidifying the plates and stabilizing the portions of the garment to which it is attached.
